Inventor

Glenn V. Burt

UNITED STATES PATENT OFFICE.

GLENN V. BURT, OF KANSAS CITY, MISSOURI.

BOTTLE CARRIER.

Application filed September 22, 1920. Serial No. 411,948.

To all whom it may concern:

Be it known that I, GLENN V. BURT, a citizen of the United States, residing at Kansas City, in the county of Jackson and 5 State of Missouri, have invented certain new and useful Improvements in a Bottle Carrier, of which the following is a specification.

My invention relates to a bottle carrier, 10 particularly adapted for use in connection with milk bottles, while not necessarily restricted to this use.

An important object of the invention is to provide a device of the above mentioned 15 character, having a lock element, so arranged that it is moved upwardly toward the locking position, by the upward movement of the hand in the act of lifting the device.

Other objects and advantages of the invention will be apparent during the course 20 of the following description.

In the accompanying drawings forming a part of this specification, and in which like numerals are employed to designate like 25 parts throughout the same,

Figure 1 is a perspective view of a device embodying my invention, viewed from the sides thereof, and,

Figure 2 is a similar view viewed from 30 the end of the same.

My device or carrier embodies a pair of approximately U-shaped members 5 and 6, which may be formed of wire, or other suitable material. The members include lower 35 jaws 7, to whip the bottle neck upon opposite sides thereof, and upstanding arms 8 and 9, are carried by the jaws. The arms 9 are bent between their ends into a horizontal pivot portion 10, pivotally receiving 40 coils 11, bent in the arms 9, as shown.

The numeral 12 designates a pair of hand grips, which may be formed of wood or the like, and having openings 13 formed in their ends, to receive laterally bent ends 14, the 45 upper portions of the arms being preferably sunk into the material of the ends, to prevent the ends from turning, upon their longitudinal axes.

The numeral 15 designates a vertically

movable locking element, extending horizontally longitudinally of the device, beneath the hand-grips. The locking element 15 has its ends bent into eyes 16, slidably receiving the arms 8 and 9.

In use, when the locking element 15 is in 55 the lower position, Figure 2, the jaws 7 are swung to the open position, for the reception of the neck of the bottle. The jaws are then closed by swinging the hand-grips 12 toward each other. In the act of picking up 60 the carrier, the fingers grasp the lock-element 15 and thereby raise it, to the position shown in Figure 1, and the lock element will be properly retained in this position by frictional engagement.

It is to be understood that the form of my invention herewith shown and described is to be taken as a preferred example of the same, and that various changes in the shape, size, and arrangement of parts may be re- 70 sorted to without departing from the spirit of my invention, or the scope of the subjoined claims.

Having thus described my invention, I claim:—

1. A bottle carrier of the character described, comprising a pair of pivotally connected approximately U-shaped members having upstanding arms, handles connected with the upper ends of the arms, and a vertically movable locking element arranged longitudinally beneath the handles and slidably engaging said arms.

2. A bottle carrier of the character described, comprising a pair of pivotally connected approximately U-shaped members having upstanding arms, hand-grips secured to the upper ends of the arms, and a locking element arranged longitudinally beneath the hand-grips and having eyes slidably receiving said arms.

In testimony whereof, I have affixed my signature in the presence of two witnesses.

GLENN V. BURT.

Witnesses:

Mrs. G. V. BURT,

Mrs. M. L. STULTS.
